ADDITION COMPOUNDS OF CYCLOHEXYL-
AMINES AND MONOCYCLIC PHENOLSGeorge L. Hockenyes, Springfield, Ill., assignor to
Monsanto Chemical Company, St. Louis, Mo., a
corporation of DelawareNo Drawing. Application March 1, 1939.
Serial No. 259,103

16 Claims. (Cl. 260—563)

The present invention relates to insecticidal and disinfectant compositions and it has particular relation to such compositions which contain as an effective ingredient a cyclohexylamine addition product of a phenol or a homologue thereof.

The main objects of the invention are to provide:

Compounds of phenol, cresol, polyphenols, or their homologues which are relatively non-odorous; which are oil soluble; which are effective in the extermination of insect and bacterial life, and which are simple and economical to prepare.

These and other objects will be apparent from consideration of the following description and the appended claims.

It has heretofore been observed that cresol and homologues thereof are highly effective as germicidal compositions and in the eradication and prevention of such insect pests as bedbugs, cockroaches, ants and the like. These compositions are normally applied as oil solutions of conventional type. While highly effective for the above described purposes, cresol and its homologues are also characterized by a strong odor which renders them objectionable for application about the home or other places inhabited by man. Although various attempts have been made to inhibit or mask the odor of these compounds, these efforts have heretofore been substantially without success.

The present invention is based upon the discovery that phenol, cresol, polyphenols, and homologues and analogues thereof may be caused to react with primary, secondary or tertiary cyclohexylamines such as cyclohexylamine, C-aliphatic-hydrocarbon-cyclohexylamines, α -alkyl cyclohexylamine, α -methyl cyclohexylamine, α -ethyl cyclohexylamine, N -methyl cyclohexylamine, N -ethyl cyclohexylamine, di-cyclohexylamine, N -2-ethylhexyl cyclohexylamine, N -octyl cyclohexylamine, N -n propyl α -methylcyclohexylamine, N -benzyl cyclohexylamine, N -dimethyl cyclohexylamine, N -diethyl cyclohexylamine, N -dibenzyl cyclohexylamine, N -amyl- N -benzyl cyclohexylamine, N -methyl dicyclohexylamine, N -benzyl dicyclohexylamine, N -phenyl cyclohexylamine, and the like. In any of the foregoing amines, and similar cyclohexylamines, the cyclohexyl group or groups may contain additional hydrocarbon radicals such as aliphatic radicals; for example, methyl, ethyl, propyl, butyl, amyl and hexyl radicals.

The addition products, formed by the reactions illustrated hereinafter, are readily soluble in light

mineral oils such as kerosene, naphtha and the usual oil vehicle employed in making up cresol solutions. These oil solutions are substantially non-odorous and still highly toxic to insect and bacterial life.

Cyclohexylamine may be regarded as a typical example of a compound falling within the above classes of amines. It reacts with cresol in the ratio of two mols of cresol to one mol of cyclohexylamine. However, since the reaction product under some conditions tends to dissociate, it is desirable to employ an excess of cyclohexylamine. Excellent results have been obtained in actual practice by employing the ingredients in the ratio of 60 parts by weight of cresol to 75 by weight of cyclohexylamine.

An inert solvent for the reactants may be employed but it is not absolutely necessary. In the event it is employed, the oil vehicle (e. g., a petroleum distillate such as is used as a vehicle in fly sprays) to be employed to make up the spray functions quite satisfactorily. The product requires no purification and by using the reaction medium as the spray vehicle substantial economies of materials and labor are effected. Of course, only a portion of the distillate required to make up the spray need be employed as the reaction vehicle. A concentrated solution may be made up and this then diluted for use. The reaction is immediate and spontaneous and is accompanied by the evolution of considerable heat.

The product is liquid and decomposes in distillation. It does not require any purification or other treatment in order to render it usable. It is quite oil soluble and may be employed with such petroleum fractions as kerosene as a vehicle. Excellent results may be obtained by reacting two and one-half parts of cresylic acid to two parts of cyclohexylamine and introducing the reaction product into ninety-five and three-fourths parts of kerosene. This solution is applied as a spray or otherwise in accordance with conventional methods against such household pests as bedbugs, cockroaches and the like.

Although substantially the full toxicity of the cresol with respect to the insects and germicidal life is retained by the reaction product of cresol and the cyclohexylamine, it is remarkable that the penetrating and disagreeable odor characteristic of cresol is entirely absent.

It is to be understood that in the above described reaction, cyclohexylamine is given merely by way of example. The cyclohexylamine may be replaced by any of the amines described hereinbefore and the cresol may be replaced by phenol

or higher homologues including mono and di ethyl, mono and di normal or isopropyl, butyl, isobutyl, amyl, hexyl and di-isobutyl phenols. The alkyl groups in these compounds may be in 5 ortho, meta, or para positions. In addition, resorcinol, catechol, hydroquinone and pyrogallol may be used instead of cresol and these polyhydroxy benzenes may be substituted by hydrocarbon radicals such as the alkyl groups mentioned 10 above. Any of the phenolic bodies may also be substituted by one or two chlorine or bromine atoms. However, the solubility of the compound in oil may in some cases be reduced by the presence of the halogen. The phenolic body is reacted 15 with any one of the herein named amino bodies in accordance with the provisions of the invention. When it is desired to accelerate the reaction, heat may be applied. The resultant products are dissolved in oil or other inert solvents 20 and used as insecticides and germicides in the usual manner.

These amines may be primary or secondary, that is, contain like or unlike aliphatic or cycloaliphatic groups attached to the same nitrogen atom and the aliphatic groups may be either 25 normal or branched chains. The corresponding diamines are also contemplated.

This application is a continuation-in-part of 30 my copending application, Serial No. 45,316, filed October 16, 1935, which has since been abandoned.

Although only the preferred forms of the invention have been described, it is to be understood that these are given merely by way of example and that numerous modifications may be made therein without departure from the spirit of the invention or the scope of the appended 35 claims.

What I claim is:

- 40 1. An addition compound of a monocyclic phenol and a cyclohexylamine, said compound being soluble in oil and possessing insecticidal properties.
2. An addition compound of a monohydroxy 45 substituted benzene hydrocarbon and a cyclohexylamine, said compound being soluble in oil and possessing insecticidal properties.
3. An addition compound of a monocyclic phenol and a cyclohexylamine having at least one hydrogen atom attached to the nitrogen atom of the cyclohexylamine, said compound being soluble in oil and possessing insecticidal properties.
4. An addition compound of a monohydroxy

substituted benzene hydrocarbon and a cyclohexylamine having at least one hydrogen atom attached to the nitrogen atom of the cyclohexylamine, said compound being soluble in oil and possessing insecticidal properties. 5

5. An addition compound of a monocyclic phenol and a primary cyclohexylamine, said compound being soluble in oil and possessing insecticidal properties.

6. An addition compound of a monohydroxy 10 substituted benzene hydrocarbon and a primary cyclohexylamine, said compound being soluble in oil and possessing insecticidal properties.

7. An addition compound of a monohydroxy substituted benzene hydrocarbon and cyclohexyl- 15 amine, said compound being soluble in oil and possessing insecticidal properties.

8. An addition compound of a cresol and a cyclohexylamine, said compound being soluble in oil and possessing insecticidal properties. 20

9. An addition compound of a cresol and cyclohexylamine, said compound being soluble in oil and possessing insecticidal properties.

10. A cresol-cyclohexylamine addition compound in which the components are combined 25 in the ratio of two molecules of a cresol and one molecule of cyclohexylamine, said compound being soluble in oil and possessing insecticidal properties.

11. An addition compound of a monocyclic 30 phenol and a secondary cyclohexylamine, said compound being soluble in oil and possessing insecticidal properties.

12. An addition compound of a monohydroxy substituted benzene hydrocarbon and a secondary 35 cyclohexylamine, said compound being soluble in oil and possessing insecticidal properties.

13. An addition compound of a monohydroxy substituted benzene hydrocarbon and dicyclohexylamine, said compound being soluble in oil and 40 possessing insecticidal properties.

14. An addition compound of a cresol and di-cyclohexylamine, said compound being soluble in oil and possessing insecticidal properties.

15. An addition compound of a monocyclic 45 phenol and a C-alkyl cyclohexylamine, said compound being soluble in oil and possessing insecticidal properties.

16. An addition compound of a cresol and C-ortho-methyl cyclohexylamine, said compound being soluble in oil and possessing insecticidal properties. 50
